(57) CLAIM

The ornamental design for an optic holder, as shown and described.

DESCRIPTION

FIG. 1 is a top perspective view of an optic holder, showing my new design;

FIG. 2 is a bottom perspective view thereof;

FIG. 3 is a top view thereof;

FIG. 4 is a bottom view thereof;

FIG. 5 is a left side view thereof;

FIG. 6 is a right side view thereof;

FIG. 7 is a front view thereof; and,

FIG. 8 is a rear view thereof.

The portions of the optic holder shown in broken lines form no part of the claimed design.
